LEMON M. REED, OF CLEVELAND HEIGHTS, OHIO, ASSIGNOR TO HATTIE E. GYNN, OF CLEVELAND HEIGHTS, OHIO.

SPRING-SEAT.

1,355,263.

Specification of Letters Patent.

Patented Oct. 12, 1920.

Application filed December 27, 1919. Serial No. 347,824.

To all whom it may concern:

Be it known that I, LEMON M. REED, a citizen of the United States, and residing at Cleveland Heights, in the county of 5 Cuyahoga and State of Ohio, have invented a new and useful Spring-Seat, of which the following is a specification.

This invention relates to improvements in spring-seats, and pertains more especially 10 to a spring-seat comprising two vertically spaced and oppositely arranged substantially horizontal plates the lower of which is adapted to be carried by a supporting member, and also comprising springs employed in supporting the upper plate from 15 the lower plate, and furthermore comprising means for guiding the upper plate relatively to the lower plate and for maintaining said plates in parallel relation and directly opposite each other.

One object of this invention is not only to have said guiding means permit descent of the hereinbefore mentioned upper plate against the action of said springs without 20 the movement of any portion of said means below the aforesaid lower plate, and to have said springs spaced circumferentially of the space between the central portions of the plates, but to have said guiding means arranged wholly in said space and composed 25 of members having such relative arrangement that the plates are relatively movable to an adequate extent and that a strong, durable and simple connection is provided between the plates for maintaining said plates 30 in parallel relation and directly opposite each other during relative movement of the plates against the action of the springs.

Another object is not only to provide each 35 plate with vertical guiding members projecting toward and spaced from the other plate but to so connect said guiding members together that each guiding member will be helpful in steadyng the other guiding members.

With these objects in view, and to attain any other object hereinafter appearing, this invention consists in certain features of construction, and combinations and relative arrangements of parts, hereinafter described in this specification, pointed out in the claims, and illustrated in the accompanying drawings.

In said drawings, Figure 1 is a side elevation, in central vertical section, of a spring-

seat embodying my invention. Fig. 2 is a horizontal section taken along the line 2—2, Fig. 1, looking downwardly. Figs. 3 and 4 are vertical sections, in detail, taken along the line 3—3 and line 4—4, respectively, 60 Fig. 1. Figs. 3 and 4 are drawn on a larger scale than Figs. 1 and 2.

Referring to Figs. 1 and 2 of said drawings, 5 indicates the upper portion of a bracket adapted to be carried by the framework or body of a tractor or other vehicle or machine, and said bracket has a rearwardly projecting arm 6 on which my improved seat is shown mounted. Said seat comprises two vertically spaced and directly 65 oppositely arranged substantially horizontal metal plates 7 the lower of which is shown mounted directly on the bracket-arm 6 and secured to said arm in any approved manner. An even number of vertically arranged helical springs 10 are interposed between the plates 7 and spaced circumferentially of the space between the central portions of the plates and support the upper plate from the lower plate. The seat- 70 proper 9 is applied to the upper plate in any approved manner. Improved means for guiding the upper plate in relation to the lower plate and for maintaining said plates in parallel relation and directly opposite 75 each other, during any vibration to which the lower plate may be subjected, are shown as comprising two horizontally spaced guiding members 11 which project vertically downwardly from the upper plate, two 80 horizontally spaced guiding members 12 which project vertically upwardly from the lower plate, and a sleeve 13 which loosely 85 embraces said guiding members and is arranged centrally between and spaced preferably equidistantly from the plates. The guiding members 11 and 12 correspond in thickness and dimensions and are preferably circular in cross section. The upper 90 guiding members 11 are secured to and rendered rigid with the upper plate in any approved manner, and the lower guiding members 12 are secured to and rendered rigid with the lower plate. Each guiding member of each plate is spaced at its free 95 end from the other plate, and preferably all of the guiding members are arranged in the space between the central portions of the plates. Preferably said guiding members are spaced forwardly and rearwardly, 100

105

110

and preferably the guiding members of each plate alternate with the guiding members of the other plate. The member forming the sleeve 13 has a vertical hole 14 for 5 each guiding member, and said hole extends vertically through the sleeve. The sleeve illustrated therefore extends forwardly and rearwardly of the seat and is provided with four holes 14 spaced forwardly and 10 rearwardly of the sleeve. The most rearward hole 14 is engaged by the rearward guiding member of the lower plate and the forward intermediate hole is engaged by the forward guiding member of said lower 15 plate, and therefore the most forward hole and the rearward intermediate hole in the sleeve are engaged respectively by the forward guiding member and rearward guiding member of the upper plate. Each 20 guiding member is shown projecting into the hole 14 engaged thereby somewhat more than half the distance between the top and bottom of the sleeve. The sleeve-embraced free end portion of each guiding member is 25 provided centrally between the top and bottom of the sleeve with a pin 15 which extends laterally through and is carried by said guiding member and projects into vertical slots 16 formed in the sleeve at opposite sides respectively of said end portion of said guiding member and consequently at opposite sides respectively of the hole engaged by said guiding member, as shown in Figs. 3 and 4. The slots 16 which are engaged by a pin 15 of an upper guiding member 11 (see Fig. 3) extend from a point approximately central between the bottom and top of the sleeve to and are open at the bottom of the sleeve and have downwardly facing upper end walls 17 which are overlapped by said pin, and obviously said pin and said slots are arranged to permit movement of said upper guiding member downwardly independently of the sleeve, and 40 said pin and said walls of said slots constitute means for preventing movement of the sleeve downwardly independently of said guiding member in the upper and normal position of the upper plate. The slots 45 16 which are engaged by a pin 15 of a lower guiding member 12 (see Fig. 4) extend from a point approximately central between the top and bottom of the sleeve to and are open at the top of the sleeve and have upwardly facing lower end walls 18 50 which are overlapped by said pin, and obviously said pin and said slots are arranged to permit movement of said lower guiding member upwardly independently of the sleeve, and said pin and said walls of said slots constitute means for preventing movement 55 of the sleeve upwardly independently of said guiding member in the normal relation of the plates. The sleeve (see Figs. 1 60 and 2) is provided with two arms 20 pro-

jecting forwardly and rearwardly respectively, and the relative arrangement of the parts is such that adjacent each arm 20 is a spring 10 and said arm extends between two adjacent coils of said spring centrally 70 between the ends of the spring. The springs adjacent the arms 20 are diametrically opposite, and said arms and said springs are helpful in holding the sleeve in position during the assemblage of the parts, as said 75 springs can be applied to the lower plate before the application of the remaining springs. Preferably before the application of said remaining springs the lower plate, the lower guiding members 12, the sleeve 13, 80 the two springs adjacent the arms 20, the upper plate and the upper guiding members 11 are assembled, and it will be observed that said arms and the last-mentioned springs coöperate in effecting downward 85 movement of the sleeve as desired independently of the guiding members of the lower plate during the compression of the springs by the descent of the upper plate independently of the lower plate.

What I claim is—

1. In a spring-seat, the combination, with two vertically spaced substantially horizontal plates the lower of which is adapted to be carried by a supporting member, each plate being provided with a guiding member projecting toward and spaced from the other plate, and springs supporting the upper plate from the lower plate, the guiding members of the plates being arranged in different vertical planes respectively, of a sleeve loosely embracing said guiding members and arranged between and spaced from the plates, the guiding member of the upper plate being movable downwardly independently of the sleeve, the guiding member of the lower plate being movable upwardly independently of the sleeve, said sleeve and the guiding member of the upper plate having means for preventing movement of the sleeve downwardly independently of said guiding member in the upper and normal position of the upper plate.

2. In a spring-seat, the combination, with two vertically spaced substantially horizontal plates the lower of which is adapted to be carried by a supporting member, each plate being provided with a vertical guiding member projecting toward and spaced from the other plate, and springs supporting the upper plate from the lower plate, the guiding members of the plates being arranged in different vertical planes respectively, of a sleeve embracing said guiding members and arranged between and spaced from the plates, the guiding member of the upper plate being movable downwardly independently of the sleeve, the guiding member of the lower plate being movable upwardly independently of the sleeve, said sleeve and

the last-mentioned guiding member having means for preventing movement of the sleeve upwardly independently of said last-mentioned guiding member in the normal 5 relation of the plates.

3. In a spring-seat, the combination, with two vertically spaced substantially horizontal plates the lower of which is adapted to be carried by a supporting member, each 10 plate being provided with a vertical guiding member projecting toward and spaced from the other plate, and springs supporting the upper plate from the lower plate, the guiding members of the plates being 15 spaced horizontally, of a sleeve loosely embracing said guiding members and arranged centrally between and spaced from the plates, the guiding member of the upper plate being movable downwardly independently 20 of the sleeve, the guiding member of the lower plate being movable upwardly independently of the sleeve, said sleeve and the last-mentioned guiding member having means for preventing movement of the 25 sleeve upwardly independently of said last-mentioned guiding member in the normal relation of the plates, and the sleeve and the guiding member of the upper plate having means for preventing movement of the 30 sleeve downwardly independently of said guiding member in the upper and normal position of the upper plate.

4. In a spring-seat, the combination, with two vertically spaced substantially horizontal plates the lower of which is adapted to be carried by a supporting member, each 35 plate being provided with a vertical guiding member projecting toward and spaced from the other plate, and springs supporting the upper plate from the lower plate, the guiding members of the plates being arranged in different vertical planes respectively, of a sleeve loosely embracing said 40 guiding members and arranged between and spaced from the plates, the guiding member of the upper plate being movable downwardly independently of the sleeve, said sleeve and the last-mentioned guiding member having means for preventing movement 45 of the sleeve downwardly independently of said guiding member in the upper and normal position of the upper plate, the sleeve having a vertical slot adjacent the free end portion of the guiding member of the lower 50 plate and extending downwardly from and open at the top of the sleeve and having an upwardly facing end wall at its lower end, and said guiding member of the lower plate having a pin projecting into said slot at the 55 last-mentioned end of the slot.

5. In a spring-seat, the combination, with two vertically spaced substantially horizontal plates each of which has a vertical guiding member projecting toward and spaced 60 from the other plate, and springs supporting the upper plate from the lower plate,

supporting the upper plate from the lower plate, the guiding members of the plates being arranged in different vertical planes respectively, of a sleeve loosely embracing said guiding members and arranged between and spaced from the plates, the guiding member of the lower plate being movable upwardly independently of the sleeve, said sleeve and the last-mentioned guiding member having means for preventing movement of the sleeve upwardly independently of said guiding member in the normal relation of the plates, the sleeve having a vertical slot which is adjacent the guiding member of the upper plate and extends upwardly from and is open at the bottom of the sleeve and has a downwardly facing end wall at its upper end, and said guiding member of the upper plate having a pin projecting into said upper end of said slot. 85

6. In a spring-seat, the combination, with two vertically spaced substantially horizontal plates each of which has a vertical guiding member projecting toward and spaced from the other plate, and an even number of vertically arranged helical springs supporting the upper plate from the lower plate and spaced circumferentially of the space between the central portions of the plates, the guiding members of the plates being spaced horizontally, of a sleeve loosely embracing said guiding members and arranged centrally between and spaced from the plates and having arms extending between coils of two diametrically opposite springs. 90

7. In a spring-seat, the combination, with two vertically spaced substantially horizontal plates each of which has a vertical guiding member projecting toward and spaced from the other plate, the guiding members of the plates being spaced horizontally, of a sleeve loosely embracing said guiding members and spaced from the plates and having a vertical slot which is formed adjacent the guiding member of the lower plate and extends downwardly from and is open at the top of the sleeve and has an upwardly facing end wall at its lower end, the last-mentioned guiding member having a pin projecting into said slot adjacent said wall, the sleeve also having a vertical slot which is formed adjacent the guiding member of the upper plate and open at the bottom of the sleeve and has a downwardly facing end wall at its upper end, and said guiding member of the upper plate having a pin projecting into the last-mentioned slot at the last-mentioned wall. 115

8. In a spring-seat, the combination, with two vertically spaced substantially horizontal plates each of which has a vertical guiding member projecting toward and spaced from the other plate, and springs supporting the upper plate from the lower plate,

the guiding members being spaced horizontally, of a sleeve loosely embracing said guiding members and having two vertical slots which are formed at opposite sides 5 respectively of the guiding member of the lower plate and open at the top of the sleeve and have upwardly facing end walls at their lower ends, the last-mentioned guiding member having a pin projecting into said lower 10 ends of said slots, the sleeve also having two vertical slots which are formed at opposite sides respectively of the guiding member of the upper plate and open at the bottom of the sleeve and have downwardly 15 facing end walls at their upper ends, and said guiding member of the upper plate having a pin projecting into said upper ends of the last-mentioned slots.

9. In a spring-seat, the combination, with 20 two vertically spaced substantially horizontal plates each of which has guiding members projecting toward and spaced from the other plate, and springs supporting the up-

per plate from the lower plate, of a sleeve loosely embracing said guiding members, 25 the guiding members of the upper plate being movable downwardly independently of the sleeve, the guiding members of the lower plate being movable upwardly independently of the sleeve, said sleeve and the guiding members of the upper plate having means for preventing movement of the sleeve downwardly independently of the last-mentioned guiding members in the upper and normal position of the upper plate, 35 and the guiding members of each plate alternating with the guiding members of the other plate.

In testimony whereof, I sign the foregoing specification, in the presence of two witnesses. 40
